UNITED STATES PATENT OFFICE.

HERBERT L. THOMPSON, OF ELGIN, ILLINOIS, ASSIGNOR TO THE MAYTAG COMPANY,
OF NEWTON, IOWA, A CORPORATION OF IOWA.

DEFLOODER FOR INTERNAL-COMBUSTION ENGINES.

1,233,526.

Specification of Letters Patent. Patented July 17, 1917.

Application filed April 27, 1916. Serial No. 93,855.

To all whom it may concern:

Be it known that I, HERBERT L. THOMPSON, a citizen of the United States, residing at Elgin, in the county of Kane and State 5 of Illinois, have invented certain new and useful Improvements in Deflooders for Internal-Combustion Engines, of which the following is the specification.

This invention relates to internal combustion engines, and particularly to an apparatus for preventing the flooding of a crank case of a two cycle gasoline engine. As is well known in this class of engines, compression is affected in the crank case, the 15 compressed charge being thereafter conducted to the explosion chamber. This practice results frequently in the collecting in the crank case of a quantity of fuel which floods the crank case, and for many obvious reasons is a serious drawback to the 20 smooth operation of the engine.

It is an object of my invention to provide automatic apparatus for continually deflooding the crank case of an engine.

25 In the drawings:

Figure 1 is a sectional view of a 2 cycle engine, provided with my apparatus.

Fig. 2 is a sectional view of my attachment.

30 Fig. 3 is a transverse sectional view of the same on the line 3—3 of Fig. 2.

In the drawings, 1 represents the fuel base of a 2 cycle gasoline engine, provided with a crank case 2, in which the charge is 35 compressed on each stroke by a mechanism forming no part of this invention, but well known in the art. I provide at the lowest point in the crank case a vertical aperture 3, connecting the crank case with the fuel 40 base. Over the outlet of the aperture 3, I secure a deflooding attachment comprising a casting 4, bolted to the bottom of the crank case by bolts such as 5, and provided with a collecting chamber 6, at the lowest point 45 of which is a passage 7 leading downwardly and then upwardly as at 8, to an outlet point 9 near the bottom of the crank case and substantially above the highest point to which the base 1 can be filled with fuel.

50 In the chamber 6 is a float 10 provided with a needle valve 11, operating in the aperture 7.

The operation of the device is as follows:

Any fuel collecting in the crank case will 55 drop down through the aperture 3 into the

chamber 6. As soon as sufficient fuel has collected in chamber 6 to raise float 10 the compression in the crank case will immediately blow this fuel out through passage 7 into the fuel base. This absolutely prevents 60 the collection in the crank case of fuel sufficient at any time to flood the same.

Claims:

1. An attachment for internal combustion engines, comprising a crank case, an automatically operable draining device adapted to drain fuel from the crank case thereof. 65

2. In an internal combustion engine, a crank case and draining device adapted to drain fuel therefrom, comprising a non-return valve adapted to prevent loss of compression in the crank case. 70

3. In apparatus of the class described, a crank case, a passageway at substantially the lowest part thereof, leading from the 75 interior of said crank case to the fuel bed, a casing covering said passageway, and comprising a chamber, a float valve in said chamber, a passageway controlled by said float valve and terminating at a point above 80 the bottom of the said chamber, whereby when fuel has accumulated in said chamber sufficiently to raise said float valve it will be blown out by compression into the fuel bed. 85

4. In apparatus of the class described, a crank case, an outlet opening at the lowest point thereof, a casing covering said outlet opening, comprising a chamber in communication with a passageway leading 90 downwardly therefrom and then upwardly to a point substantially above the bottom of said chamber, a check valve in said chamber controlled by a float and adapted to close said passageway unless said float is 95 raised by liquid in said chamber, whereby when liquid has drained from said crank case into said chamber sufficiently to raise said float, the liquid will be blown out of said chamber by compression in said crank 100 case.

5. An attachment for internal combustion engines, comprising a casing having a chamber therein adapted to drain fuel oil from the crank case, a float in said chamber, a 105 passageway controlled by said float, said casing being adapted to be secured upon a drain opening in the crank case of an engine.

6. In an internal combustion engine, a 110

fuel bed, means to limit the height of the liquid therein, a crank case mounted on said fuel bed, a drain opening communicating from said crank case to said fuel bed, an attachment in said fuel bed and covering said drain opening, a chamber in said attachment, a passageway leading from said chamber into said fuel bed, the point of outlet from said passageway into said fuel bed being substantially above the highest fuel level in said fuel bed, and a float valve in said chamber controlling said passageway substantially as described.

7. An attachment for internal combustion engines having a crank case comprising a 15 draining device adapted to automatically drain the crank case without loss of compression.

In witness whereof, I hereunto subscribe my name to this specification in the presence of two witnesses. 20

HERBERT L. THOMPSON.
